land, Ohio, a corporation of Ohio

Application June 20, 1933, Serial No. 676,673

4 Claims. (Cl. 271—76)

This invention relates to printing presses, and more particularly presses of rotary character; and it is among the objects of the invention to provide equipment for high speed throughput of web feed and cut sheet flat delivery. Other objects and advantages will appear as the description proceeds.

To the accomplishment of the foregoing and related ends, the invention, then, comprises the features hereinafter fully described, and particularly pointed out in the claims, the following description and the annexed drawings setting forth in detail an illustrative embodiment of the invention, this being indicative however, of but one of the various ways in which the principle of the invention may be employed.

In said annexed drawings:

Fig. 1 is a side elevational view of an embodiment of the invention, parts being broken away; Fig. 2 is a plan view of the assembler portion thereof; and Fig. 3 is a vertical section taken on a plane substantially indicated by line III—III, Fig. 2.

Referring more particularly to the drawings, there is shown rotary printing press means comprising cylinders 2, 3, 4, 5, operating upon a web *w* of paper, printing the same on both sides, the construction of the printing press being along known lines, and preferably of perfecting newspaper press character, and requiring no further particularly detailed showing. As many webs *w*, *w'* as desired, each similarly coming from such printing cylinders, are brought together by the guide rolls 6, 7, in the end frame 8. Adjacent the latter is a frame 9 within which is mounted a revolving knife 10, carried by a shaft 11 which is geared in step with the press rolls, through the intermediary of gearing 12, 13, 14, sprocket chain 15, shaft 16, bevel gearing 17, and shaft 18 which is coupled to the printing press drive. Mounted adjustably on a block 20 on the frame 9 is a stationary blade 21 which coacts with the revolving blade 10. Above the knife 21 is a guide plate 22 and guide rolls 23, 24, the latter being surfaced to maintain the paper smooth, as for instance by divergent ribs 25.

Below the stationary knife blade 21 is an apron guide 26, and a sloping conveyor belt 27 in the form of narrow strands or tapes; and interdigitating therewith is another conveyor 28 almost horizontally positioned between rollers 29, 30. Beyond the latter belt and at a slightly lower level is a further conveyor 31 between rollers 32 and 33. Upper conveyor tapes 34 are positioned above, in relation to form guides. The conveyor

27 is driven by sprocket chain 35, running over its roller 36, on a shaft in common with the sprocket receiving the chain. Conveyor 28 is similarly driven by drive belt 35 running under the sprocket 29 on its roller shaft. Conveyor 31 is driven by a drive belt 37 which takes over a cone pulley 38 for adjustment of speed. Drive belt 35 is also engaged over a cone pulley 39, for speed adjustment. The frame 40 carrying the conveyor 31, etc. and fitting within the standards of the frame 9, also carries a pair of racks 41 upon which are mounted guide rolls or trolleys 42, for maintaining the sheets in smooth condition in transit. At the end of the frame 40 is a discharge roller or rollers 43, which engage the sheets and throw them in turn upon the delivery table 44, in suitable jogging guides at the ends and sides thereof (which may be of known detail and require no further showing). The delivery table 44 is lowered in proportion with the increasing stack, by lowering means 45, which may also be of known detail, and requires no further showing.

Webs of paper *w*, *w'* etc. proceeding between the printing cylinders are printed on both sides and brought together between the guide rolls 6 and 7, and passed thence through the guide rolls 23, 24, and over the inclined plate 22 to the cutter 10, 21. The cut sheets feed down thence onto the conveyor 27, and then to the conveyor 28, from which they are forwarded to conveyor 31. By setting the cone drive 38, 39, appropriately, the speed of conveyor 31 may be adjusted to 10-80 per cent that of the web feed further back, and the sheets are thereby caused to correspondingly overlap in accumulating succession, the assembled sheaves of sheets being thence discharged by the discharge rolls 43 to fall onto the receiving table 44.

It is thus seen that an assembled flat delivery of completely printed sheets may be had in consistent drive from a press of newspaper perfecting character, such as to make possible a wide range of delivery conditions.

Other modes of applying the principle of the invention may be employed, change being made as regards the details described, provided the means stated in any of the following claims, or the equivalent of such, be employed.

I therefore particularly point out and distinctly claim as my invention:

1. Delivery means for receiving sheets from printing and cutting machines, which comprises an inclined conveyor receiving the cut sheets, a further conveyor, a frame supporting said conveyor, overhead guide-rolls above said last-

mentioned conveyor, and rack and pinion means in said last-mentioned frame for adjusting said guide-rolls.

2. Delivery means for receiving sheets from 5 printing and cutting machines, which comprises an inclined conveyor receiving the cut sheets, a further conveyor, a frame supporting said conveyor, overhead guide-rolls above said last-mentioned conveyor, rack and pinion means in said 10 last-mentioned frame for adjusting said guide-rolls, a receiving table, and discharge rolls for discharging sheets from said last conveyor to the said table.

3. Delivery means for receiving sheets from 15 printing and cutting machines, which comprises an inclined conveyor extending below the cutter of such cutting machine, a substantially horizontal conveyor adjacent said first-named conveyor,

another conveyor beyond and below said last-named conveyor, a frame carrying said last conveyor, guide rolls above said last-mentioned conveyor, rack and pinion means in said last frame for adjusting said guide rolls, a receiving table, and discharge rolls in the end of said frame for discharging the sheets onto said table.

4. Delivery means for receiving sheets from printing and cutting machines, comprising a frame independent of but fitting within the frame of such cutting machine, a conveyor in said frame for receiving the cut sheets, a further conveyor receiving the sheets from said first-mentioned conveyor, and overhead guide means above said last conveyor regulable longitudinally 80 with relation thereto.
